United States Patent Office.

ALBERT LAURENCE MURPHY, OF PHILADELPHIA, PENNSYLVANIA.

Design No. 4,556, dated January 3, 1871.

DESIGN FOR A RAILING FOR CEMETERY LOTS.

The Schedule referred to in these Letters Patent and making part of the same.

I, ALBERT LAURENCE MURPHY, of Philadelphia, county of Philadelphia, State of Pennsylvania, have invented or produced a Design for a Railing for Cemetery Lots, &c., of which the following is a specification.

In the accompanying drawings, which represent a side view of a railing made according to my design—

A A are posts, which may be surmounted with funereal urns, and which are connected together by rails B B, each railing having a central ornament, *a*, too clearly illustrated in the drawings to need description.

Claim.

The design for a cemetery railing, substantially as described, and illustrated in and by the accompanying drawings.

In testimony whereof I have signed my name to this specification in the presence of two subscribing witnesses.

ALBERT LAURENCE MURPHY.
